UNITED STATES PATENT OFFICE

2,446,582

ADJUSTABLE DISPENSER FOR COMMINUTED MATERIALS

Ernest Gopner, Elmwood Park, Ill.

Application July 8, 1947, Serial No. 759,570

1 Claim. (Cl. 222—308)

1

My invention relates to devices for dispensing granular or comminuted materials.

An important object of my invention is to provide a device of the aforementioned character, in which the dispenser is provided with an adjustable measuring compartment so as to adjustably feed, within the range of adjustment, varied quantities of granular or comminuted materials stored in the body of the dispenser, or in the container associated with the said dispenser.

A further object of my invention is to provide a device of the aforementioned character, which is operable alternately by oscillating the control means within an angular range to and fro; each movement ejecting a dose filled a priori, and filling and measuring a dose simultaneously, to be ejected on the return movement.

A still further object of my invention is to provide a dispenser of the aforementioned character provided with agitator means adapted to agitate the comminuted materials immediately prior to their being fed into the measuring pockets provided in the said dispenser device.

A further object of my invention is to provide adjustably controlled wings, manipulatable from a single source; the said wings being anchorably secured to a flat spring structure, the flexure, or bowing outwardly or inwardly of the said flat spring effectuating a larger or smaller adjustment of the said measuring and dispensing pockets.

A further object of my invention is to provide a device of the aforementioned character, which is simple in construction but practical for the purposes for which it may be utilized, and of such simple, elemental structure as to warrant economical manufacture thereof in quantity production.

Other objects, added advantages, and ancillary features inherent in my invention will become apparent to persons skilled in the art from an examination of the accompanying drawings, bearing further elucidation in the ensuing description, wherein like symbols are used to designate like parts, and in which:

Fig. 1 represents a perspective view with certain portions thereof cut away, and with certain elements therefrom shown in an exploded arrangement, so as to more clearly depict the essential details of my invention.

Fig. 2 is a perspective view of one of the wing sections, and its method of anchorage to the flat adjusting spring comprising an important feature of my invention.

2

Fig. 3 is a front view of the dispenser head of my invention.

Fig. 4 is a view looking in the direction of arrows 4—4 on Fig. 3.

5 Fig. 5 is a view looking downwardly in the direction of arrows 5—5 on Fig. 3.

Fig. 6 is a cross-sectional view taken substantially on the lines 6—6 of Fig. 3.

Referring to the various views, my invention

10 is generally designated 9, and consists of a body 9 and a container 8 secured to the said body. The said container may be made of metal, plastic, or preferably transparent material, so as to show the diminution of the contents as they are consumed during operation and usage of the device.

The body 9 is provided with a number of hanging ears 10 so that the entire structure may be easily hung upon a wall. The body 9 tapers 20 downwardly to form the pyramidal walls 11, terminating in a cylindrical section 12 covered and enclosed by the bottom 13, provided with an ejection port 14. The section 12 has fitted therein the rotor element, which is designated 19,

25 and consists of a semi-cylindrical enclosure confined by the top, bottom, and walls 20 on a diametral line connected to a hub 18. The said hub also has a triangular extension at the forward part thereof 46', on which the wings 21,

30 comprising an important feature of my invention, ride during adjustment. The said wings are shown in detail in Fig. 2 and comprise a top wall section 27, a downwardly depending wall 31, having a slotted portion therein 32, for receiving 35 movably, in suitable anchorage arrangement, the slotted portion 26 of the flat spring 21.

The top surfaces or walls 27 ride on the wall 46 of the rotor 19. The said rotor is manipulated through the knob 15, which has a reduced 40 threaded extension 16, the tip of which, designated 17, rests against the boss or central hub 18 heretofore designated. The threaded portion of the stud 16 serves to operate the nut 22 permitting the same to ride thereupon forwardly or 45 backwardly, the said nut being riveted at 23 to the flat spring 21, thus causing the said spring 21 to be bowed outwardly, in which event the wings are brought closer together, providing the largest feeding pocket arrangement, or when the nut 22 rides toward the tip 17 of the screw, the flat spring is distended spreading the wings and reducing the size of the pockets 45 and 46, which are to be known in this application as the measuring pockets.

55 The knob 15 is confined in place by the inser-

tion of a U-shaped clip 24, made of wire or other suitable material, engaging an inner filleted portion on the stem of the screw 16 positioned inwardly of the wall 25, thus confining the screw 17 from longitudinal movement in or out, hence compelling the nut 22 to be moved in or out by virtue of the rotation of the knob 15 in accordance with the arrows indicated in Fig. 1.

The wings are provided with an arcuate bearing portion 28, an arcuate or semi-circular opening 29, and an angularly formed or cut away portion 30 so as to permit of a range of adjustment between the said angular portions 30, thus limiting the movement of the wings in one direction; the edges 41 limiting the movement of the wings in the opposite direction.

The central hub portion is provided with a reduced extension 33, having a threaded opening 34, the extension 33 serving as a bearing for the bearing recesses 29 of the wings 27. The entire structure is confined by the plate 36 which is properly located in assembly by virtue of the key 35 engaging the keyway 31 in the said plate. The said plate is provided with a central opening 41 to fit over the extension 33, and is confined in place by means of the screw 40 which engages the threaded opening 34. The said screw also serves the added function of securing the agitator 42 by virtue of its enlarged central hub portion 43.

When the handle 15 is moved within the slot 14 from end to end, one of the openings 33 or 33 is caused to align with one of the pockets 45 or 46, in turn aligning one of the said pockets 45 or 46 with the discharge opening 44. Thus, while one dose is metered out through the exhaust port 44, another charge is being deposited on the bottom 13 ready for the movement of the knob 15 in the opposite direction when the said charge will be ejected, while a new charge is being deposited through the registration of the other opening in the plate 36. To effectuate an adjustment, the knob is rotated, in the direction of the arrows 48, clockwise or counter-clockwise depending on whether the wings are to be brought together, or separated. When the knob is oscillated in the direction of the arrows 49, the material confined within the pockets 45 and 46 is alternately being discharged; when one is discharging, the other is filling, and vice-versa. When the wings are spread apart, they narrow the confines of the pockets 45 and 46, and vice-versa.

Assuming that a charge of granular or comminuted material is in the pocket 46, ready to be discharged by movement of the knob 15 and, before discharging the same, it is decided to change the dosage, or the volume of the compartments 45 and 46, by rotating the knob in the proper direction, the material confined therein will be forced upwardly into the container, and thus the adjustment may be made at any time prior to the actual dispensing of the granular ma-

terial. Simultaneously with the movement of the knob 15 in the direction of the arrows 49, the agitator 42 is also moved back and forth agitating the granular material. Such a device may be used conveniently as a granular coffee retainer, or for flour, or other substances which are occasionally metered out in accordance with recipe requirements, and hence the agitator 42 serves an admirable function in this respect. In view of the fact that such materials, when they remain static for some time, have a tendency to pack tightly, agitation is a very important function needed in the handling of such materials.

I believe I have described and illustrated, rather succinctly, the nature and the construction of my invention and, inasmuch as the same is susceptible of modifications, alterations, and improvements, I hereby reserve the right to all modifications, alterations, and improvements coming within the scope and spirit of my invention, as well as any that may be implied by the preferred embodiment illustrated and embraced in the drawings, and as well any improvements that may fall within the purview of the foregoing disclosure; my invention to be limited only by the subjoined claim.

Having thus described and disclosed my invention, what I claim as novel, and desire to secure by Letters Patent, is:

30 A dispenser for comminuted materials comprising, a body provided with a container retaining portion at its top and a cylindrical extension at its bottom, a slotted portion in the said cylindrical extension located on its peripheral surface, a semi-cylindrical rotor rotatably confined in the said cylindrical extension defining two measuring pockets in the said cylindrical extension, manipulating means passing through the said slot and resting against the 40 central portion of the said rotor, the said manipulating means being provided with a threaded stem portion, means rotatably securing the said stem portion preventing longitudinal movement thereof, a pair of wings angularly and adjustably disposed and pivotably secured to the central portion of the said rotor, resilient means threadably secured at its midpoint to the said threaded stem portion and having its termini secured to the 50 said wings, and a cover plate secured to the central portion of the said rotor confining the said wings rotatably and adjustably.

ERNEST GOPNER.
